INVENTOR:

Frederick Rapp, by
Emile & Russell, his Atty.

UNITED STATES PATENT OFFICE.

FREDERICK RAPP, OF CHICAGO, ILLINOIS.

WATCH-CASE HINGE.

SPECIFICATION forming part of Letters Patent No. 313,449, dated March 3, 1885.

Application filed August 28, 1884. (Model.)

To all whom it may concern:

Be it known that I, FREDERICK RAPP, of Chicago, in the county of Cook and State of Illinois, have invented certain new and useful Improvements in Hinge-Joints for Watch-Cases; and I do hereby declare that the following is a full, clear, and exact description thereof, reference being had to the accompanying drawings, in which—

10 Figure 1 is a perspective view of a watch-case containing my improved hinge. Fig. 2 is a like view of the parts of the hinge separated from each other. Fig. 3 is a perspective view of one of the case-center lugs, with 15 its pivotal pin in the position occupied when the cover is connected with said case-center, and Figs. 4 and 5 are sections upon a line passing through the axes of the pivotal pins, and show, respectively, the positions of the 20 latter when engaged with and disengaged from the case-cover portion of said hinge.

Letters of like name and kind refer to like parts in each of the figures.

My invention relates to a watch-case hinge 25 which is contained entirely within the case, and has for its object the ready connection and separation of the cover and case-center portions of the same; to which end said invention consists, principally, in a hinge for watch-cases in which are employed two pivotal pins 30 that are each caused to engage with the adjacent lug by an endwise movement, and when thus engaged are locked in place by a screw or other equivalent means, substantially as 35 and for the purpose hereinafter specified.

It consists, further, in a hinge for watch-cases in which each outside lug is provided with an axial opening that contains a pivotal pin which by an endwise movement may be 40 caused to project beyond the end of said lug and to enter into and engage with an axial opening in the adjacent end of the center lug, substantially as and for the purpose herein- 45 after shown.

45 It consists, finally, in a hinge for watch-cases in which each outside lug contains a pivotal pin that is adjustable endwise for the purpose of engagement with the center lug, and is locked in position by means of a set- 50 screw which passes inward through said outside lug, substantially as and for the purpose hereinafter set forth.

In the annexed drawings, A represents a watch-case center, within the interior of which are secured two hinge lugs, B and B, that are 55 relatively arranged to permit of the insertion between their inner ends of a third lug, C, that is attached to a cover, D. Said lug C is secured at one end to the inner side of said cover, inside of the bearing-edge *d* of the same, 60 and extends in a curve downward and outward, so as to bring its opposite outer end into position between said lugs B. An opening, *a*, formed within said case-center, partly or wholly within the bearing-face *a'*, that is 65 provided for said bearing-edge *d*, permits of the inward passage of said lug C, the arrangement being such that said hinge-lugs are contained wholly within the case, and are not seen when said case is closed.

70 Within each lug B is provided an opening, *b*, which coincides axially with a similar opening, *b*, in the opposite lug B, and contains a pivotal pin, E, that may be entirely withdrawn within said lug, or may be caused to 75 project beyond the inner end of the same. The center lug, C, is provided within each face with a recess or opening, *c*, that coincides with the opening *b* of the contiguous lug B, and is adapted to receive the end of the pin 80 E, contained within the latter, when said pin is moved inward and caused to project beyond the same.

To connect the cover D with the center A, the lug C is placed in position between the 85 lugs B, and the pivotal pins E moved inward until in engagement with the openings or recesses *c*, after which each of said pins is secured in place by means of a set-screw, F, that passes inward through its lug B and im- 90 pings upon said pin.

While the arrangement of lugs as shown is preferably employed, the outside lugs may, if desired, be secured to the cover and the center lug secured to the case-center.

95 I do not herein claim, broadly, pivotal pins when arranged to move longitudinally to engage with the adjacent lug or lugs, the same being covered by another application for patent, Serial No. 141,647.

100 Having thus fully set forth the nature and merits of my invention, what I claim is—

1. A hinge for watch-cases in which are employed two pivotal pins that are each caused

to engage with the adjacent lug by an end-wise movement, and when thus engaged are locked in place by a screw or other equivalent means, substantially as and for the purpose specified.

- 5 2. A hinge for watch-cases in which each outside lug is provided with an axial opening that contains a pivotal pin which by an end-wise movement may be caused to project beyond the end of said lug and to enter into and engage with an axial opening in the adjacent end of the center lug, substantially as and for the purpose shown.
- 10 3. A hinge for watch-cases in which each

outside lug contains a pivotal pin that is adjustable endwise for the purpose of engagement with the center lug, and is locked in position by means of a set-screw which passes inward through said outside lug, substantially as and for the purpose set forth.

15 20 In testimony that I claim the foregoing I have hereunto set my hand this 18th day of August, 1884.

FREDERICK RAPP.
